UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

MINING AND LOADING MECHANISM.

1,378,361.

Specification of Letters Patent.

Patented May 17, 1921.

Application filed April 7, 1915, Serial No. 19,746. Renewed July 31, 1920. Serial No. 400,546.

To all whom it may concern:

Be it known that I, NILS D. LEVIN, a citizen of the United States, residing at Columbus, in the county of Franklin and State of Ohio, have invented certain new and useful Improvements in Mining and Loading Mechanism, of which the following is a specification, reference being had therein to the accompanying drawings.

10 The invention relates especially to mining and loading mechanisms of the class in which each comprises means for forming a transverse horizontal kerf at the base of the coal face, means for breaking down the coal thus undercut, and a conveyer arranged to extend into the undercut and to receive and carry away the coal which is broken down. A number of mechanisms of this general character have already been invented by 15 myself and others, and the object of this invention is to provide a mechanism of this class which shall be free from some of the disadvantages incident to the earlier machines.

20 Most of the earlier machines can be divided into two distinct sub-classes, as follows: (1st) those in which the coal face is attacked along lines perpendicular thereto, the machine as a whole being fixed against

25 lateral movement while operating. Some of the machines of this sub-class were intended to be moved laterally between cuts so as to be thus advanced along the coal face and across the room; and other machines 30 of this sub-class were intended only to be moved continuously forward to simply cut a narrow tunnel or entry; (2nd) those machines which were movable bodily laterally while operating, some of the machines of

35 this class being adapted for movement along straight lines parallel to a straight kerf, and others being adapted for movement along curved lines parallel to a curved face. 40 Machines embodying my present invention belong to the second of the above mentioned classes. One of the characteristic features of difference between this machine and earlier machines is that it is free for movement either inward or along the coal

45 face, and is provided with means for cutting a kerf during movements in either of the said directions. The machine is actuated, guided and controlled entirely by means of flexible cables which permit it to be moved 50 as desired under the control of the operator.

to conform to the varying conditions of the coal to be mined and loaded.

One object of the invention, therefore, is to provide a continuously operating mining and loading machine which can be moved 60 while operating either inward to make a sumping cut or parallelly to the coal face, preferably in either direction. Another object is to provide, in combination with the cutting, breaking down and loading devices, 65 improved actuating, guiding and controlling elements. A further object is to provide an improved general arrangement of parts for a machine of this character. A still further object is to provide a combined 70 mechanism comprising improved conveying devices supplemental to the primary conveyer which initially receives the broken down coal. Further objects will be apparent from the following specification and 75 claims.

In the accompanying drawings I have illustrated one embodiment of the invention, but it will be understood that many modifications and changes may be made 80 without departing from the spirit of the invention.

Referring to the drawings,

Figure 1 is a plan view of the cutting, breaking down and loading parts of the 85 mechanism.

Fig. 2 is a side view on a smaller scale, looking toward the left of the parts shown in Fig. 1.

Fig. 3 is a fragmentary plan view with 90 some of the parts in section, showing the cutting chain and associated parts.

Fig. 4 is a combined elevational and sectional view taken along the line 4—4 of Fig. 1.

Fig. 5 is a sectional view taken along the line 5—5 of Fig. 1.

Fig. 6 is a side view of the parts shown in Fig. 5.

Fig. 7 is a sectional view taken along the 100 line 7—7 of Fig. 1, the cutter chain being removed for the sake of simplicity.

Fig. 8 is a fragmentary sectional view taken along the line 8—8 of Fig. 1, the cutter chain being removed for the sake of 105 simplicity.

Fig. 9 is a detailed view of the support for the breaking down device.

Fig. 10 is a fragmentary sectional view taken along the line 10—10 of Fig. 3.

Fig. 11 is a fragmentary sectional view taken along the line 11-11 of Fig. 3, the cutter chain being removed in this view for the sake of simplicity.

5 Fig. 12 is a detailed view of the stop block.

Fig. 13 is a perspective view of the intermediate conveyer.

10 Fig. 14 is a longitudinal sectional view through the driving end of the intermediate conveyer.

Fig. 15 is a side elevation, partly in section, of the final or delivering conveyer.

15 Figs. 16 to 23 are diagrammatic views illustrating one manner of using the mechanism.

The machine comprises a main base frame 20 adapted to slide over the floor of the mine in any direction, a cutting mechanism projecting from the inner end of the base frame, 25 propelling and guiding devices mounted upon the base frame, a conveyer attached to the cutting mechanism to be carried thereby into the kerf produced in the coal body, a motor mounted upon the base frame, 30 suitable driving connections between the motor and the cutting mechanism, the conveyer, the propelling and the guiding mechanisms respectively, and a breaking down device mounted upon the base frame and adapted to break the coal down upon the conveyer.

Referring to the construction in detail, 35 the base frame comprises a bottom plate 1 adapted to slide over the floor of the mine. This plate 1 is attached to the depending flanges 2 of the bed frame casting 3 upon which are mounted the other parts of the machine. Supported by the depending 40 brackets 3^a from the under side of the bed frame casting, and adapted to limited longitudinal movement thereon, is a cutter frame 4. The cutter frame comprises a bottom plate 5 on which are placed a chain 45 guide bar 6 and stiffening bars 7 and 8. Upon these bars are placed the top plates 9 and 10, and all of the parts are securely riveted together, as shown. Guide strips 11 are secured along the edges of the plates 50 to engage the links of the chain 12 to prevent their accidental removal from the guide ways thus formed. The chain 12 can be of standard construction and it need not be described in detail. It is provided with cutters 12^a. The outer surface of the guide bar 6 is protected by a renewable wearing strip 13 over which the chain slides. The top plate 9 is cut away at 14 to form a slot the edges of which engage the aforesaid bracket 60 3^a, which carries an adjusting screw 15 in threaded engagement with the nut casting 16 attached to the bottom plate 5. By means of the screw 15 it is possible to move the cutter frame for the adjustment of the tension of the cutter chain 12 in the manner

common to chain cutter mining machines. The cutter frame is extended laterally and rearwardly along the right hand side of the machine for a purpose which will presently appear, and on account of the unbalanced strains due to this extension, there is preferably provided a second adjusting screw 17, carried by a casting 18 secured to the bottom plate 1 and engaging the rear edge of the cutter frame to maintain the frame in proper alignment with the base frame 3. Clamping bolts 19 and 20 extending through slots in the cutter frame enter threaded apertures in supporting blocks 21 secured to the bottom plate 1 to assist in holding the parts in their proper working relation.

Mounted upon the base frame casting 3 is an electric motor 22 having an armature 23 mounted in suitable bearings 24 and 25. Secured to the shaft of this armature is a spur pinion 26 engaging with a spur gear 27 mounted upon a shaft 28 journaled in bearings on the base frame casting. The spur gear 27 is connected through a friction disk safety device 29 with a bevel pinion 30 which meshes with the master bevel gear 31. Any overload transmitted to the bevel pinion 30 from the master gear 31 will cause a slippage of the friction disks of the safety device 29 and prevent the overrunning of the motor. The master gear 31 is fixed on a vertical shaft 32 which is journaled in the bearings 33 of the base frame casting and in the bearing 34 of an auxiliary frame secured thereto. Mounted upon the lower end of the vertical shaft 32 is a sprocket wheel 35 by which the cutter chain 12 is driven. Suitable clutch mechanism is interposed between the sprocket wheel 35 and the vertical shaft 32 by which they may be connected or disconnected as the conditions of operation may require. As concerns this clutch there can be variation, but for purposes of illustration I have shown the shaft 32 as provided with an apertured flange 32^a. The sprocket wheel 35 is similarly apertured and in a central recess of the wheel is a ring which carries vertical pins 35^a adapted to extend through both sets of apertures. When the pins are in the position shown the sprocket wheel is connected to the shaft, but by lifting the pins they can be disengaged from the flange 32^a, thus breaking the power connection to the sprocket wheel 35.

Formed on the hub of the bevel gear 31 is a worm 36 which engages the worm wheel 37 keyed to the shaft 38 extending across the machine and supported in the bearings 39, 40 and 41 attached to the base frame casting 3. Mounted upon this shaft 38 is a cable winding drum 42 upon which may be wound the cable 43 by which the machine may be moved and guided about the 130

working place as will be later explained. Upon one side of this drum 42 is formed the driven member 44 of a friction clutch of the well known Weston multiple disk type, 5 the driving member 45 of which is keyed to the shaft 38. Attached to the clutch member 44 is an inward extending flange 46 provided with a central screw threaded aperture engaging similar threads on the 10 hub of a spur gear 47. The gear 47 is freely mounted upon the shaft 38 in such a manner that the rotation of the gear 47 relative to the clutch member 44, in one direction will actuate the clutch to drive the drum 15 and in the other direction will release it. Convenient means for the manipulation of the spur gear 47 is provided in the pinion 48 attached to the shaft 49 journaled in suitable bearings of the machine frame, and 20 having its end squared to fit a convenient wrench for manual rotation.

A second friction clutch 50, similar to the clutch above described, is mounted on the shaft 38 and upon the driven member of this 25 is formed a spur pinion 51 which engages a spur gear 52 keyed to the shaft 53. A spur gear wheel 54 is provided for the manipulation of the clutch 50, and this gear is controlled by the spur pinion 55 attached to the 30 shaft 56 adapted to be controlled with a hand wrench in the same manner as the first described clutch. To the shaft 53 is fixed a pinion 57 engaging the gear wheel 58 to drive the feed shaft 59 and with it the feed 35 drum 60. A feed cable 61 is attached to the drum 60 to be wound thereon to feed the machine to its work as will be later explained.

Positioned at suitable points about the 40 machine are guide sheaves 62, 63, 64, 65, and 66 by which the feed cable 61 may be led in any desired direction for the proper manipulation of the machine, as will be fully set forth, and a swiveled sheave 67 is provided 45 adjacent to the drum 42 by which the cable 43 may be guided in either direction.

A convenient reverse switch 68 is provided by which the direction of rotation of the armature 23 may be controlled. Starting 50 and stopping of the motor is effected by the starting box 69 having a handle 70 located convenient to the hand of the operator.

The conveyer is of the endless chain and scraper type and is carried by a self-contained structure having a forward horizontal part lying in a recess of the cutter frame and an inclined rearward portion extending along the right hand side of the motor frame, to a point in the rear of the feed and guiding 55 mechanism to discharge the coal into any receptacle placed conveniently to receive it.

The forward horizontal portion of the structure comprises two parallel side rails 71 which have secured to them the angle bars 65 72. To these angle bars are attached the

plate 73 which forms the bottom of the conveyer trough. Formed in the side rails 71 are notches adapted to engage the square-headed studs 74 fixed to the bottom plate 5 to prevent longitudinal movement of the 70 conveyer structure. Cover plates 75, bolted to the upper frame, engage the upper edges of these side rails to hold them in place. The chains of the conveyer are indicated by 75 79 and are provided with rollers 78. Because of the difficulty of properly lubricating the bearings of a revolving shaft continually exposed to dust in the limited space available at the forward end of the cutter frame, the foot shaft 76 is fixed to the side 80 rails 71 and upon the surface of this shaft are formed two circular flanges 77 upon the periphery of which the rollers 78 of the conveyer chains 79 travel. The carrier strand of the conveyer chains 79 and the cross bars 85 80 travel on the plate 73 to push the coal along the trough, and the return strand travels over the bottom plate 5 to a point 81 near the foot shaft 76 where the plate is cut away to afford additional clearance. 90

The inclined rear portion of the conveyer structure comprises two side plates 82 and 83, attached at their forward ends to the side rails 71. To these side plates are fixed the angles 84 which support the trough plate 73, 95 and the angles 85 which support the return strands of the chains 79. Angles 86 secured to the side plates 82 and 83 protect the chains from contact with the coal in the trough. Channel bars 87 and 88, secured to the main frame 3 of the machine, and vertical angle bars 89 secured to these channels form a structure which supports the rear end of the conveyer. Secured to the side plates 82 and 83 near their rear end, are adjustable journal boxes 90 of the type commonly used in conveyer practice to afford means for tensioning the conveyer chains, and in these is journaled the head shaft 91 having suitable sprocket wheels which engage the conveyer chain to drive it. The shaft 91 is connected by means of the sprocket wheel 92 and the chain 93 with the sprocket wheel 94 fixed upon the transverse shaft 95 journaled in bearings 96 of the machine frame and driven by the bevel gears 97 and 98 from the vertical shaft 32 to drive the conveyer. A removable side plate 99 is provided for use at the forward end of the conveyer after the completion of the 115 summing cut. Secured to the back of this plate 99 are attachment lugs 100 adapted to be inserted in apertures 101 provided for their reception in the plates and bars of the cutter frame. The use of this removable plate will 120 appear in the description of the operation of the machine as hereinafter set forth.

As concerns the breaking down mechanism, there can be wide variation, but I prefer a mechanism which consists of a me- 130

chanically operated pick of any suitable type, such as is commonly used for undercutting coal. Although any one of a number of well known mechanisms might be used, I have shown, for purposes of illustration, a pneumatically actuated pick mechanism of a well known manufacture, having a cylinder 102 within which is a piston carrying a tool 103 adapted to reciprocatory motion. Compressed air is supplied from any convenient source through a suitable air hose 104 and controlled by a conveniently placed valve 105. Formed on the sides of the cylinder 102 at about its center of weight are trunnions 106 adapted to be supported in suitable bearings of a yoke 107 which is pivoted for rotation in a horizontal plane, in the hub 108 of the goose neck bracket 109. Convenient handles 110, attached to the rearward end of the cylinder 102, afford means to direct the blows of the pick against any desired point in the coal face. Formed at the other end of the bracket 109 is a hub 111 in which are mounted the ball bearings 112, 113, and 114, the inner races of which engage the pivot post 115 fixed in the top and bottom plates 116 and 117 of the horizontally oscillatable arm 118, affording a support for the bracket 109 and the parts carried thereby. The ball bearings, being sufficiently massive, afford an abutment for the thrust of the pick against the coal face as transmitted through the trunnions 106, the yoke 107 and the bracket 109. Hinged to the bracket 109 is a latch 119 adapted to engage with notches in the segmental plate 121 attached to the arm 118 concentric with the pivot post 115 to prevent the rotation of the bracket about the pivot. A cord 122 attached to the latch 119 and leading around the guide sheave 123 to the hand of the operator at the handle 110, affords means for disengaging the latch when such rotation is desirable.

The arm 118 is built up of the top and bottom plates 116 and 117 and the channel bars 124, and is pivotally attached to the supporting platform 125 by the pivot bolt 126. The platform 125 comprises the plate 127 supported from the motor frame 22 by two sections of channel bar 128 bolted to the motor frame and riveted to the plate 127, and of an angle bar 129 fixed to the forward edge of the plate 127 and extending above the conveyer and along the right hand side of the machine and supported by angle bars 89 and 89^m of the machine frame. Spaced apertures in the angle bar 129 are adapted to receive the lugs 131 of the stop block 132 by which the oscillation of the arm 118 may be limited.

In mines adapted for the room and pillar system of mining, entries or passages, along which the coal is transported, are excavated in the coal body and from these entries open

the rooms in which the principal mining operations are conducted. Tracks are laid along the entries for the passage of the cars in which the coal is hauled, and from these tracks extend branches into the rooms. For reasons which it is not necessary to recite at this time, these branch tracks are usually laid along one side of the room, and as the mining operations extend across the end of the room much of the coal must be carried a considerable distance to be loaded into cars standing upon such tracks. On this account I have found it advisable to use an auxiliary conveyer, extending along the working face in such relation thereto that it will receive the coal discharged from the machine conveyer, as it is advanced across the face, and deliver the same to an auxiliary loading conveyer which in turn delivers it to the cars.

As illustrated in Fig. 13, the auxiliary face conveyer comprises a trough 133, of similar construction to that used in the inclined portion of the conveyer upon the mining machine, which is supported at either end on pedestals 134 and 135, each provided with a sole plate 136 and 137 respectively, adapted to slide over the floor of the mine in any direction, to facilitate placing the conveyer in working relation with the mining machine. Along the trough 133 travel two endless strands of the chains 138 connected together at intervals by cross bar scrapers 139 by which the coal is propelled along the trough. A head shaft 140 and a foot shaft 141 are provided at the ends of the trough to guide the chains 138 in the manner common to conveyer practice. A driving shaft 142, journaled in suitable bearings supported by the trough structure, carries sprocket wheels 143 which engage the return strands of the chains 138 to drive them, and idler sprockets 144, suitably mounted, hold the chains 138 in working engagement with the sprocket wheels 143. The drive shaft 142 is connected through the sprocket wheels 145, the chain 146 and the sprocket wheel 147 with the motor 148, mounted in the pedestal 134.

The loading conveyer is preferably, though not necessarily, similar to that forming a part of the mechanism shown and described in my co-pending application for mining and loading machines, Serial No. 782,522, filed August 1st, 1913. It is illustrated in Fig. 15, and comprises two sections of trough 149 and 150, the former of which extends in an upward inclined direction while the latter extends in an approximately horizontal direction above the cars 151 standing on the rails 152 of the mine track. These trough sections are connected together by a horizontal hinge 153 to admit of a certain amount of vertical adjustment of the delivery end of the trough 150. Se-

cured to the trough 150 are forward extending arms 154 connected through the links 155 with the cross yoke 156 which is in threaded engagement with the adjusting screw 157 by which the said adjustment may be effected. This loading conveyer is supported on a structure comprising a hopper casting 168, adapted to slide over the floor of the mine, and a steel framework 179, built up of structural shapes suitably connected together and to the hopper casting according to the practice of structural steel construction. An axle 180 and wheels 181, adapted to travel on the rails 152 of the mine track, are provided to support the weight of the rear portion of the framework 179 and to facilitate the positioning of the conveyer for service. The hopper casting 168 is shaped to form the forward portion of the conveyer trough, and is provided with suitable bearings in which is journaled the foot shaft 182. At the rearward extremity of the horizontal section 150 are fixed journal boxes 183 of the ordinary adjustable type commonly used in conveyer practice to regulate the tension of the conveyer chains 184. The conveyer chains 184 pass around the sprocket wheels of the head and foot shafts in the manner common to scraper conveyers, and are connected together at intervals by the cross bar scrapers 185 which slide over the bottom plates of the troughs 149 and 150 to propel the coal therethrough. Mounted in suitable bearings of the structural frame 179 is a shaft 186 which is so positioned that the line of the return strand of the conveyer chain 184 is approximately tangential to the periphery of the sprocket wheels 187 mounted thereon. These sprocket wheels 187 engage the chains 184 to drive them, a sufficient amount of slack being provided to insure engagement with the teeth of the wheels. The shaft 186 is driven through suitable gearing from the motor 179 mounted upon the framework 179.

As illustrated in Fig. 16, according to the preferred method of use, the machine is placed near the right hand rib, adjacent the working face, with the forward end of the cutting frame as close up into the corner as is convenient. The feed cable 61 is then drawn out from the drum 60, passed around the guide sheave 62 and secured to a suitable jack 188 at the face. The guide cable 43 is then drawn out from the drum 42, passed around the swiveled sheave 67 and the guide sheave 65 and anchored at 189 adjacent the right rib. When the machine is started, and the feed cable 61 wound upon the drum 60, the machine will be caused to move forward to make the sumping, or entering, cut.

By the manipulation of the friction clutches 44 and 50, the drums 42 and 60 may be caused to wind their respective ca-

bles 43 and 61, to hold them against unwinding or to allow them to freely unwind as the operator may desire. By such manipulation of the clutches the guide ropes will be controlled to bring the machine into the position shown in Fig. 17.

As soon as the cutter frame, with the forward end of the machine conveyer, is sufficiently advanced beneath the coal, compressed air will be admitted to the breaking down mechanism, and as its tool 103 reciprocates, the operator will direct its strokes against the desired point in the coal face to break out fragments upon the conveyer to be removed thereby.

While the machine is operating as illustrated in Figs. 16 and 17 the face conveyer 133 is adjusted to receive the coal from the delivery end of the machine conveyer and the loading conveyer is adjusted to receive coal from the face conveyer and deliver it to a car 151 placed to receive it.

After the machine has been drawn the maximum distance into the coal, the jack 188 is removed to a point adjacent the left rib, as illustrated in Fig. 18, and the feed cable 61 is connected thereto. The rope or cable feeding and guiding mechanism is then manipulated to feed the machine across the face. As the machine advances the pick mechanism breaks down the coal and the conveyers carry it to the car. The operation will thus be continued until practically the entire width of the room has been traversed, and the machine will be in the position indicated in Fig. 19. If now the feed drum 60 be held against rotation and the guide cable 42 be wound up, the rear end of the machine will be drawn toward the right, and forward end of the cutter frame forced to the left to finish the cut, as illustrated in Fig. 20.

The feed rope 61 will then be passed around the guide sheaves 63, 64, 65 and 66 to the anchor jack 189 positioned as illustrated in Fig. 21, and the machine again sumped into the coal to the position illustrated in Fig. 22. The conveyers will then be again adjusted relative to the mining machine and the operation repeated in the reverse direction, as illustrated in Fig. 23.

When mining machines of the usual weight and dimensions are used, and it is desired to cut first in one direction and then in the other, it has been found necessary to reverse the cutter bits in the cutter chain and reverse the direction of the chain, to prevent the bit reaction from forcing the machine away from the coal face, and I do not mean to exclude constructions of this sort. But experience with the machine embodying my invention as described has demonstrated that the additional weight of the breaking down and conveying mechanisms prevents the movement of the ma-

chine by such reaction and it is possible to cut in both directions without changing the bits or reversing the chain.

As soon as the sumping cut is completed 5 in either side of the room the removable plate 99 is adjusted to confine the broken coal to the conveyer, and when the cut has been completed across the room this plate will be again removed to be out of the way 10 while sumping.

I am aware of the fact that machines for mining and loading have been heretofore made or proposed, each of which had in combination chain under-cutters, conveyers, 15 and reciprocating picks for breaking down means; but the machines referred to were of the "breast" class; that is to say, had their parts so designed and related that the kerf was formed by a thrust of the cutting 20 apparatus directly inward from the front face, the kerf across the face being, as an entirety, composed of a series of these direct inward thrust cuts. The machines did not cut continuously along the face. 25 The pick mechanisms used with these earlier machines were not arranged in such a way as to form a widely extended and inwardly extended vertical broken face running from the normal front face to the vertical plane of the inner end of the cut. The picks were designed to break down the front face over an area of the width of that of the under-cut.

In the present case the purpose is to continuously form a uniformly wide under-kerf extending along the face (in contradistinction from a crescent-shaped or arch-shaped cut), and while this kerf is being made to apply powerful blows to the coal in 35 such a way that the breaking down action shall occur along a newly formed vertical face which is transverse to or intersects the front face so that the coal can be received and carried away by a conveyer, and with 40 the apparatus much simpler and more compactly arranged than that found necessary with the earlier machines of the other class referred to.

As above indicated, the cutter mechanism 50 is arranged so that, when looked at in plan view, it travels in a path having the part A which is inclined to the vertical longitudinal planes of the machine, the part B which is approximately parallel to said planes, and the part C which is transverse thereto. The coal breaking pick mechanism is so positioned that the lines on which the blows from the pick are delivered can be close to lines that are perpendicular 55 to the vertical plane of that part of the cut which is made by that part of the cutting apparatus indicated by A. When the frame with the undercutter is being advanced to 60 make the sumping cut into the coal, the pick mechanism is also advanced, and begins to

make the shear cut next to the right hand rib, as shown in Figs. 16 and 17; and, therefore, when the time comes to re-adjust the feeding and checking mechanism to make the cross cut, the pick has opened up a vertical chamber, as shown in Fig. 18, which exposes a face inclined to the normal, or front face of the coal, and the pick operates toward this inclined face while the machine is being propelled toward the left. When 70 it reaches the predetermined extremity of its travel on lines perpendicular to the face, the inclined part A of the cutter path permits the machine, as an entirety, to swing around and make a perfectly square rib or 80 room wall at the left hand side as shown in Fig. 20. The pick, being mounted in the way devised, acts as above stated so as to break down the coal above the undercut up to the line of the left hand wall or rib, it being possible to adjust it so that its pivots are 85 outside of the coal face and yet its longitudinal axial line will be approximately perpendicular to the vertical plane of the line of the part A of the cutter path. 90

The pick, being mounted on a frame or support such as described, can be thrown bodily forward or backward. By swinging the supporting frame or arm 118 forward or backward, the main positioning can be 95 effected. Then, by adjusting the arm 109 around in relation to the part 118, a still closer positioning to the desired points can be attained for the pick.

What I claim is:

1. In a machine for undercutting, breaking down and loading coal, the combination of a horizontal cutter frame, a kerf cutting mechanism having operative parts at the front and at the inner end of the said frame, whereby a kerf can be cut when the frame is moving either inward or forward, a conveyer having its receiving end positioned within the outlines of the frame and between the upper and lower cutting planes of the 110 said cutting mechanism and having its delivery end above the said planes, and means above the receiving end of the conveyer for breaking down the coal. 105

2. In a machine for undercutting, breaking down and loading coal, the combination of a horizontal cutter frame, a kerf cutting mechanism having operative parts at both sides and at the end of the said frame, whereby the kerf can be cut when the frame 120 is moving either inward or in either direction parallelly to the coal face, a conveyer having its receiving end positioned within the outlines of the frame and between the upper and lower cutting planes of the said cutting mechanism and having its delivery end above the said planes, and means above the receiving end of the conveyer for breaking down the coal. 125

3. In a machine for undercutting, break- 130

ing down and loading coal, the combination of a horizontal cutter frame, a kerf cutting mechanism having operative parts at the front and at the inner end of the said frame, whereby a kerf can be cut when the frame is moving either inward or forward, a conveyer having its receiving end positioned within the outlines of the frame and between the upper and lower cutting planes of the 5 said cutting mechanism and having its delivery end above the said planes, means above the receiving end of the conveyer for breaking down the coal, and a removable plate adapted to be secured at the rear of 10 the conveyer when the machine is moving forward.

4. In a machine for undercutting, breaking down and loading coal, the combination of a horizontal cutter frame, a kerf cutting 20 mechanism having operative parts at both sides and at the inner end of the said frame, whereby a kerf can be cut when the frame is moving either inward or in either direction parallelly to the coal face, a conveyer having 25 its receiving end positioned within the outlines of the frame and between the upper and lower planes of the said cutting mechanism and having its delivery end above the said planes, means above the receiving end 30 of the conveyer for breaking down the coal, and a removable plate adapted to be secured at whichever side of the conveyer is rear-most when the machine is moving parallelly to the coal face.

5. In a machine for undercutting, breaking down and loading coal, the combination with a main frame adapted to be moved in any direction relative to the coal face, power actuated devices mounted upon said main 40 frame to move and guide said main frame, a horizontally extending cutter frame carried by the main frame, cutting devices carried by said cutter frame and adapted to cut a kerf near the base of a coal vein when the 45 machine is moved longitudinally inward or laterally in either direction, a continuously acting conveyer having a receiving portion disposed within the bounding planes of the kerf cutter and extending to near its inner 50 extremity, and breaking down devices comprising a reciprocating pick mounted upon a universally adjustable pick holder permanently attached to the main frame, said pick being adapted to strike the coal on lines extending either parallel to or transversely of 55 the normal face of the vein to break down the coal above the conveyer.

6. In a mechanism for under-cutting, breaking down and loading coal, the combination of a main frame, power driven devices thereon for moving said frame laterally along the face of the coal, a horizontal frame adapted to extend from the main frame forward into a kerf at the bottom of 60 the coal and travel therein laterally when

the main frame is advanced as aforesaid, a chain cutter moving around the cutter frame, a conveyer positioned in vertical planes at the side and parallel to the vertical longitudinal planes of the main frame and 70 having its receiving end positioned within the outline of the cutter frame and adapted to move in the said bottom kerf, a breaking down mechanism comprising a reciprocating pick and cylinder bodily adjustable laterally 75 and inward and outward relatively to the receiving end of the conveyer, and a support for the breaking down mechanism comprising a horizontally swinging arm pivoted to the main frame, and a manually controllable 80 lock for securing the arm in either of several positions.

7. The combination of the main frame, the power devices thereon, the horizontally projecting undercutting mechanism, means 85 for moving the frame and the undercutter bodily along the coal face, the coal breaking pick mechanism, and the support for the pick mechanism adjustably connected to the main frame to position the pick mechanism 90 bodily either outside the vertical planes of the coal face or inside of said planes.

8. The combination of the relatively wide main frame, the power devices thereon, the horizontally projecting undercutter mechanism, the conveyer on the frame having its receiving end adapted to enter the kerf of the undercutter, means for moving the frame with the aforesaid parts along the face of the coal, and the coal breaking pick 100 mechanism mounted on the frame and adapted to be bodily adjusted from positions outside of the planes of the normal coal face to positions inside of said planes.

9. In a mechanism for under-cutting, breaking down and loading coal, the combination of a main frame, power actuated means thereon for moving said frame laterally along the face of the coal, a cutter frame projecting horizontally forward from the main frame and adapted to travel therewith laterally in a kerf near the bottom of the coal, an endless chain cutter traveling around said frame in a path having a section at the inner end approximately parallel 110 to the coal face, a section inclined inward and backward relatively to the longitudinal lines of the main frame, and a section which is approximately parallel to said longitudinal lines, a breaking down mechanism comprising a reciprocating pick and a holder therefor which is permanently mounted on the main frame and is adjustable laterally and inward and outward, whereby the lines of the blows of the pick can be optionally 115 varied relatively to the plane of the broken down coal face which extends from the front face to the vertical plane of the inner terminal of the kerf.

10. In a mechanism for under-cutting, 130

breaking down and loading coal, the combination of the main frame, propelling devices adapted to advance said frame toward a coal face on lines inclined to the latter, or to project it on lines approximately parallel thereto, a cutter frame extending forward and also laterally backward from the main frame, a chain cutter traveling around said cutter frame, a conveyer in vertical planes at the side and parallel to the vertical longitudinal planes of the main frame and intersecting the front part of the cutter frame, said conveyer having its inner end adapted to travel in a kerf at the bottom of the coal,

a breaking down mechanism and a horizontally adjustable frame projecting laterally from the main frame and across the vertical longitudinal planes of the conveyer for supporting the breaking down mechanism, said breaking down mechanism having a reciprocating pick and pick holder, the pick being arranged to form a broken coal face extending in either of two opposite directions from the normal front face to the vertical planes of the inner terminal of the undercut.

In testimony whereof I affix my signature.
NILS D. LEVIN.
